SMOKER'S ASH RECEIVER

Emil A. Hirner, Allentown, Pa.; The Allentown National Bank administrator of said Emil A. Hirner, deceased

Application August 26, 1935, Serial No. 37,888

3 Claims. (Cl. 131—51)

This invention relates to ash receivers useful to smokers.

As ordinarily constructed, smokers' ash receivers have rests transversely of their edges for the support of cigarettes and cigars. When the cigarettes, for example, are left burning on the rests of such receivers, the unconsumed ends extending outwardly of the tray edges eventually overbalance the lighted ends, whereupon the cigarettes topple over and fall beyond the confines of the receivers with attendant burning and soiling of table covers or marring of the finish of the furniture on which the receivers are supported. Moreover, by reason of projecting beyond the ash receivers, the burning cigarettes are often accidentally displaced from the supports with like disastrous results.

My invention is directed toward obviating the contingencies which have been mentioned. This objective I attain in practice, as hereinafter more fully disclosed, through provision, in connection with smoker's ash receivers, of rests for supporting cigarettes or the like with assurance against easy displacement accidentally, and in such manner that, upon becoming unbalanced when left to burn, they will fall into the receivers where they can do no harm to table covers or furniture.

My invention is capable of embodiment in a variety of alternative forms, of which several examples are herein illustrated and described.

In the drawings, Fig. I shows in top plan view, a smoker's ash receiver conveniently embodying the present improvements.

Fig. II is a longitudinal sectional view of the receiver taken as indicated by the arrows II—II of Fig. I.

Fig. III is a transverse sectional view taken as indicated by the arrows III—III of Fig. I.

Figs. IV and V are views corresponding to Figs. I and II showing a slightly modified form of ash receiver.

Fig. VI shows in plan an alternative embodiment of my invention; and

Fig. VII shows the sectional profile of the modified receiver featured in Fig. VI along the plane indicated by the arrows VII—VII in that figure.

The ash receiver featured in Figs. I—III is intended to be used for both cigars and cigarettes, and as shown, is of oblong configuration with side walls 1 and 2, and end walls 3 and 4 all of substantial thickness. The side walls 1 and 2 it will be observed, converge downward complementarily at a relatively sharp angle toward the bottom 5 of the receiver; while the end walls 3 and 4 are but slightly pitched inwardly toward

the bottom, all of said walls being beveled outwardly at the top as at 6 to avoid broad ledges whereon cigars or cigarettes might be rested. Extending inward from each of the side walls 1 and 2 at the center of the receiver is a pair of spaced, upwardly-tapering projections 7 having deep V-shaped notches 8 in their tops capable of supporting either cigarettes C or cigars C' horizontally in parallel relation to the side walls 1 and 2 within the confines of the receiver, and of retaining said cigarettes and cigars against the possibility of easy accidental displacement. As shown, the V notches 8 are well spaced from the side walls 1 and 2 so that the cigars C' or cigarettes C can be grasped by two fingers in the intervals 9 between the lugs 7 and thus easily removed after the manner indicated in dot-and-dash lines at the right hand side of Fig. III; or they may be removed by inserting a finger beneath them and rolling them out of the notches 8 and over the edges of the side walls 1, 2 toward the thumb as shown in dot-and-dash lines at the left of Fig. III. In order to facilitate the removal of the cigarettes C and cigars C' in the manner just described, the walls 1 and 2 are gouged inwardly at a sharp angle as at 10 in the intervals 9 between the supporting projections 7. To further facilitate placement and removal of cigars C' upon the rests 7, the end walls 3 and 4 are provided with notches 11 and 12 in line 30 respectively with the retaining notches 8 in said rests.

Should a cigarette C be left burning on either pair of the projections 7 and eventually become unbalanced, it will obviously fall into the tray 35 rather than out of it; while ashes dropping from said cigarette as it burns, will be deflected toward the center of the receiver as a consequence of the slope of the side walls 1 and 2.

The modified form of ash receiver featured in Figs. IV and V is also rectangular like the receiver of Figs. I—III but of a smaller size and intended for use more particularly for cigarettes C alone on card tables. As in the first instance, the side walls 1a and 2a of the receiver are sharply sloped and the end walls 3a and 4a inclined at a lesser angle to the bottom 5a of the receiver. The spaced rest lugs 7a extending inward from the side walls 1a, 2a have small V notches 8a in their tops of a size to conveniently retain and support cigarettes C horizontally well inward of the wall edges; and said side walls are gouged at a deep angle as at 10a in the intervals 9a between the supporting projections 7a to provide clearances for the fingers and thereby facilitate 55

tate placement and removal of the cigarettes C. Also as shown, the end walls 3a and 4a are notched centrally as at 12, and the inner faces of said walls gouged with a taper as at 13 in continuation of such notches. By virtue of this, the end walls 3a and 4a are narrowed so that it is impossible to rest cigarettes on them.

The ash receiver featured in Figs. VI and VII is of hexagonal configuration with alternate long and short walls 1c, 2c, 3c and 15, 16, 17 respectively. Extending inwardly from the long walls 1c-3c at the center are relatively wide single lugs 7c with transverse notches 8c in their tops for support and retainment, as shown, of cigarettes C horizontally in parallelism with said sides within the confines of the receiver. The lugs 7c, it will be noted, are gouged centrally as at 9c and the walls 1c-3c gouged exteriorly as at 10c to provide clearances for the fingers 20 and thereby facilitate removal of the cigarettes C in the manner shown in dot-and-dash lines at the right of Fig. VII. The short walls 15-17 of the receiver are raised at their centers as at 18 and thickened as at 19, and moreover formed 25 with notches 20 which taper downward to slightly inwardly declining shoulders 21 at the normal level of said walls. Below the shoulders 21, the notches 20 are suddenly constricted as at 22. Holders are thus afforded into which cigars C' 30 may be pressed as shown to rest transversely of the walls 15-17 upon the declining shoulders 21. The wedging action of the tapering holders obviously prevents easy accidental dislodgment of the cigars C' after they have once been placed. 35 If cigarettes C are placed within the narrow portions 22 of the notches, they will be directed into the receiver by the slope of the walls 15-17, as shown in dot-and-dash lines at the left of Fig. VII.

40 All the trays herein illustrated may be cast or otherwise fashioned from metals, or molded from glass or ceramic materials as desired, the shaping in each instance being such that press dies can be readily used in the economic manufacture of them from moldable substances.

45 The ash receivers herein illustrated are of course to be considered as exemplary of other possible forms within the scope of the appended claims.

Having thus described my invention, I claim:

1. As a new article of manufacture, a smoker's ash receiver integrally formed from moldable material with downwardly-convergent side walls, pairs of spaced upwardly tapering projections extending inward from such side walls and having retaining notches in their upper edges for receiving and supporting cigars or cigarettes parallel with the side walls and within the confines of the receiver, said recesses being spaced from the receiver walls and the portions of the latter intermediate the taper projections grooved out inwardly to facilitate grasping of a cigar or cigarette between the finger and thumb in the intervals between said supporting projections. 5

10 2. As a new article of manufacture, a smoker's ash receiver integrally formed from moldable material with downwardly convergent side walls, pairs of spaced upwardly-tapering projections extending inward from such side walls and having V-shaped retaining notches in their upper edges for receiving and horizontally supporting cigars or cigarettes parallel with the side walls and within the confines of the receiver, said recesses being spaced from the side walls and the portions of the latter intermediate the tapering projections being grooved out inwardly at a sharp angle to facilitate grasping of a cigar or cigarette between the finger and thumb in the intervals between said supporting projections, 15 20 25 30

3. As a new article of manufacture, a smoker's ash receiver of polygonal configuration with alternating long and short inwardly sloping side walls, said long walls having relatively wide inwardly extending central projections with transverse notches therethrough for horizontally supporting cigarettes within the confines of the receiver, and the short walls being centrally raised and thickened and having notches therethrough at the thickened portion, said notches tapering downwardly to form slightly inwardly-declining supporting shoulders for cigars, and said last- 35 40 45 mentioned notches having a cross-section below said shoulders adapted to sustain cigarettes at an inclination lit ends downward.

EMIL A. HIRNER.
